UNITED STATES PATENT OFFICE.

SAMUEL J. LARGE, OF BRISTOL, CONNECTICUT, ASSIGNOR TO AMERICAN SILVER COMPANY, OF BRISTOL, CONNECTICUT.

DESIGN FOR A SPOON.

SPECIFICATION forming part of Design No. 35,929, dated June 3, 1902.

Application filed May 10, 1902. Serial No. 106,842. Term of patent 7 years.

To all whom it may concern:

Be it known that I, SAMUEL J. LARGE, a citizen of the United States, residing at Bristol, in the county of Hartford and State of Connecticut, have invented and produced a new and original Design for a Spoon, of which the following is a specification, reference being had to the accompanying drawings, forming part thereof.

Figure 1 is a plan view of a spoon, showing my new design. Fig. 2 is an edge view of the same.

As shown in the drawings, the narrow portion or shank 3 of the handle has a slightly rounded central bead 4 extending from near the junction of the handle with the bowl 5 outwardly for about two-thirds of the length of the said handle. On each side of the bead 4 there are two narrow and nearly parallel beads 6 7, with scroll-like ends turned inwardly, as shown, and terminating a little short of the outer or upper end of the central bead 4. A short distance from the outer or upper end of the bead 4 there is substantially

an oval plain portion 8, bordered on each side by two narrow beads 9 10, the handle at this point being wider than at any other part. Above the oval portion 8 there is a pointed tip 11, the face of which is provided with combined scroll and leaf ornaments in relief, as shown. At the lower or inner end of the oval portion there is a similar cluster of ornaments 12, the said ornaments and those on the tip 11 having the appearance of spreading from the oval portion and clasping its border. The space on each side of the bead 4, between the narrow beads 6 7 and the ornaments 12, is covered by scroll and leaf ornaments 13, all as shown.

Having described my invention, what I claim as new, and desire to secure by Letters Patent, is—

The design for a spoon as herein shown and described.

SAMUEL J. LARGE.
